(57) **ABSTRACT**

A new Poinsettia plant named 'EURZ0001' particularly
distinguished by its pink flower color, relatively large inflo-
rescences with the bracts a little upright directed, early
flowering response, dark green foliage, ovate leaves with
only weak lobes, and medium to strong growth habit with
good branching.

2 Drawing Sheets

1

Latin name of the genus and species of the plant claimed:
Euphorbia pulcherrima.
Varietal denomination: 'EURZ0001'.

BACKGROUND OF THE NEW PLANT

The present invention comprises a new Poinsettia, botani-
cally known as *Euphorbia pulcherrima*, and hereinafter
referred to by the variety name 'EURZ0001'.

'EURZ0001' is a product of a planned breeding program.
The new cultivar has pink bract color, relatively large
inflorescences with the bracts a little upright directed, early
flowering response, dark green foliage, ovate leaves with
only weak lobes, and medium to strong growth habit with
good branching.

'EURZ0001' originates from an induced mutation
selected in Enkhuizen, Netherlands in November-December
2011 among flowering greenhouse plants of the parent
variety.

The parent was the commercial plant designated
'SYEP22432', also known as 'Titan Red', and patented as
U.S. Plant Pat. No. 22,035, with bright red bract color,
somewhat larger dark green leaves, upright and vigorous
habit, and early flowering response.

2

Young plants of the parent variety had been exposed to a
mixture of X-ray and Gamma irradiation in Enkhuizen,
Netherlands. The treated plants were then grown out in a
greenhouse Enkhuizen, Netherlands.

During the flowering season in November-December
2011, 'EURZ0001' was discovered and selected as a single
mutated plant. The first asexual propagation was made a few
months later, by taking shoot tip cuttings from the mutated
plant, which were grown out and used for the first flowering
trial in Enkhuizen, Netherlands in the fall of 2012. Since
then, the plant has been repeatedly asexually reproduced by
cuttings in Enkhuizen, Netherlands, and found to be true to
type, uniform and stable for the new characteristic.

BRIEF SUMMARY OF INVENTION

Horticultural examination of plants grown from cuttings
of the plant initiated in the summer of 2012, and continuing
thereafter, has demonstrated that the combination of char-
acteristics as herein disclosed for 'EURZ0001' are firmly
fixed and are retained through successive generations of
asexual reproduction.

'EURZ0001' has not been observed under all possible
environmental conditions. The phenotype may vary signifi-

cantly with variations in environment such as temperature, light intensity and day length.

Plant Breeder's Rights for this cultivar were applied for in Canada on Jul. 2, 2014, No. 14-8381 and in the European Union (CPVO) on Feb. 2, 2015, No. 2015/0271.

The following traits have been repeatedly observed and are determined to be basic characteristics of the new variety. The combination of these characteristics distinguishes this Poinsettia as a new and distinct variety.

BRIEF DESCRIPTION OF THE PHOTOGRAPHS

The accompanying photographic drawing shows typical flower and foliage characteristics of 'EURZ0001' with colors being as true as possible with an illustration of this type. The photographic drawings show flowering potted plants of the new variety. FIG. 1, shows a close view of the flower bracts, FIG. 2, a view from above on a young flowering plant, and in FIG. 3, a view of a whole plant in full flower.

DETAILED BOTANICAL DESCRIPTION

The measurements were taken in Hauwert, Netherlands in mid-December 2014 on about 20 week old plants growing in a greenhouse. Culture of these plants had started in late July 2014 with planting of rooted cuttings into 12 cm pots and terminal pinching about 2 weeks later. The plants were grown under natural day light in the fall (no black cloth to initiate earlier flowering) and at the moderately warm temperature of 18° C. for the bench heating.

The aforementioned photographs: FIG. 1 was taken in Hauwert, Netherlands in mid-December 2014. The plants were from the greenhouse trial described above. FIG. 2 was taken in Monroeville, N.J. on Nov. 20, 2013 at the start of the natural flowering season, and FIG. 3 shows a plant in full flower from an exhibition ('Pack trials') taken on Apr. 15, 2015 in Gilroy, Calif.

Color references are made to The Royal Horticultural Society Colour Chart (R.H.S.) 2001.

TABLE 1

DIFFERENCES BETWEEN THE NEW VARIETY 'EURZ0001' AND A SIMILAR VARIETY

	'FISMIRPINK' (Commercially 'Mira Pink', not patented)		EURZ0002
Bract color:	51 A-C	53D	2 D
Leaf blade length:	5 cm	4-4.5 cm	6.5 cm
Bract shape	Ovate, with shallow lobes	Ovate to almost deltoid, with deep lobes	Ovate, with very shallow lobes
Internodes:	Longer	Shorter	
Plant habit:	more open	More compact	more open
Cyathia, maturity:	Later	Earlier	
Plant habit	More upright	Wider, branches more horizontally directed	

Plant:

Form, growth and habit.—Shrub, with the branches slanting upright, good branching.

Plant height (inflorescence included).—About 20 cm.

Plant width.—About 40 cm.

Roots:

Number of days to initiate roots.—18-20 days at about 24 degrees C.

Number of days to produce a rooted cutting.—24-26 days at 24 degrees C.

Type.—Fine, fibrous, free branching.

Color.—RHS N155B but whiter.

5 Foliage:

Arrangement.—Alternate, 6-9 leaves per branch.

Immature, leaf color, upper surface.—Approximately RHS 143A.

Immature, leaf color, lower surface.—RHS 144A.

Mature, leaf color, upper surface.—RHS 139A.

Mature, leaf color, lower surface.—RHS 137B.

Length.—5 cm.

Width.—7-10 cm.

Shape.—Ovate, with 2 to 4 shallow lobes.

Base shape.—Rounded.

Apex shape.—Acuminate, a little twisted sometimes.

Margin.—Entire; lobes, if present, are usually rounded.

Aspect.—Leaf blades are downwards directed.

Texture, upper surface.—Smooth.

Texture, lower surface.—Smooth, apart from the protruding veins.

Color of veins, upper surface.—RHS 144B at the base.

Color of veins, lower surface.—RHS 144C.

Petiole color, upper surface.—RHS 177B.

Petiole color, lower surface.—RHS 152D.

Length.—Most often 5-6 cm.

Diameter.—0.2 cm.

Aspect.—Horizontally to upward directed.

Texture.—Glabrous.

Stem:

Quantity of main branches per plant.—About 4.5.

Color of stem.—Mainly RHS 144A; RHS 175D at the top section (topmost 2-3 cm of the length).

Length of stem.—13-15 cm.

Diameter.—0.7 cm.

Length of internodes.—3 cm.

Texture.—Glabrous.

Color of peduncle.—RHS 144B to RHS 144C.

Length of peduncle.—0.2-0.3 cm.

Peduncle diameter.—0.2 cm.

Texture.—Glabrous.

Inflorescence:

Type.—Terminal cyme with surrounding whorl of colored bracts.

Flowering, botanically (opening of the stamen, shedding of pollen).—Around December 1.

Flowering, commercially (sufficiently colored bracts).—In about mid-November.

Flowering response time.—About 6.5 weeks from equinox.

Duration of flowering.—Depends much on light and environment; a minimum of 4-6 weeks of 'shelf' life.

Fragrance.—Absent.

Shape of inflorescence.—Rosette-like whorl, star-shaped, not quite closed in the center; bracts horizontally to upward directed.

Diameter of inflorescence.—25-27 cm.

Inflorescence, vertical diameter.—5-10 cm.

Number of completely colored bracts per inflorescence (sized over 2 cm).—12-14.

Single bract, shape.—Ovate with relatively long, pointed tips, without or with very weak lobes.

Bract, apex.—Acuminate.

Bract, base.—rounded.

Single bract, length of blade.—11.5-12 cm, younger bracts diminishing in size.
Single bract, width of blade.—8.8 cm.
Bract color, upper side.—Ranges from RHS 51A for young bracts to RHS 51C for the older and larger bracts.
Bract color, lower side.—Near RHS 51D.
Vein color, upper surface.—RHS 47B.
Vein color, lower surface.—Approximately RHS 48A.
Texture.—Weakly rugose, glabrous.
Bract petiole color, upper surface.—RHS 185A.
Bract petiole color, lower surface.—RHS 183D.
Bract petiole, length.—About 2.0-3.0 cm, shorter with younger bracts.
Bract petiole diameter.—0.2-0.3 cm.
Cyme (true inflorescence):
Cyme, diameter.—1.5 cm.
Number of cyathia.—8-9, borne in a tight cluster.
Cyathium, shape.—Ovate.
Cyathium, diameter.—0.4-0.5 cm.
Cyathium, length.—0.6 cm.
Color.—RHS N144A and N144B, with RHS N144B mostly at the base.
Nectar cups.—Usually one per cyathium.
Nectar cup, width.—0.3 cm.
Nectar cup, color.—RHS 30D, very light.

5

10

15

20

25

Reproductive organs:

Stamen (actually reduced male florets).—Usually in a small bunch of 10-20 at the top of the cyathium.

Shape.—Strap-like.

Filament length.—0.4-0.5 cm.

Filament color.—RHS 45B.

Anther color.—RHS 11A.

Anther diameter.—0.1 cm.

Pollen quantity.—Moderate (normal quantity).

Pollen color.—RHS 12A.

Female flowers.—Not observed in this trial; appear (if at all) in mid-winter, as occurrence depends much on light intensity; appear about 4 weeks later than the stamen: a single female flower emerges from the top of the cyathium with a short pedicel.

Fertility/seed set.—Has not been observed on this plant.

Disease/pest resistance: Disease/pest resistance has not been observed on this plant.

What is claimed is:

1. A new and distinct variety of Poinsettia plant named 'EURZ0001', substantially as illustrated and described herein.
